Des. 221,768
Patented Sept. 7, 1971

221,768

INFANT'S BATHTUB

John Savedra, Downsview, Ontario, Canada, assignor to
Tek Plastics Limited, Malton, Ontario, Canada

Filed Mar. 30, 1970, Ser. No. 22,105

Term of patent 14 years

Int. Cl. D23—02

U.S. Cl. D23—52

FIG. 1

FIG. 4

FIG. 5

FIG. 1 is a perspective view of an infant's bathtub showing my new design;

FIG. 2 is a top plan view thereof;

FIG. 3 is an elevational view taken from one end thereof;

FIG. 4 is a cross sectional view taken on line 4—4 of FIG. 2; and

FIG. 5 is a cross sectional view taken on line 5—5 of FIG. 2.

I claim:

The ornamental design for an infant's bathtub, as shown.
